UNITED STATES PATENT OFFICE

ALFRED POTT, OF ESSEN-ON-THE-RUHR, GERMANY

PURIFICATION OF COAL DISTILLATION GASES

Application filed January 7, 1929, Serial No. 330,971, and in Germany January 14, 1928.

The problem with which the invention is concerned, is to subject coal distillation gases, which have ordinarily been exposed beforehand to the usual purification, to a super-purification with the object of removing residues or traces of naphthalene from the gas, so that a gas, which according to present methods of investigation is free from naphthalene, is discharged into the adjoining conduits. The naphthalene content of coal distillation gases which discharge for instance into town mains at a low pressure or into long distance mains at a higher pressure, has always involved the greatest difficulty, since in the course of time it may cause sectional contraction or clogging of the mains. If the gas for any unavoidable reasons, should cool below the temperature at which it has been introduced under pressure into the conduit, and at which it contains naphthalene in vapor form, it is impossible to prevent more or less extensive deposition of solid naphthalene, which adheres to the walls of the conduit and at first forms incrustations, but in the course of time leads to appreciable contraction or even clogging of the passages.

Attempts were therefore made to remove naphthalene from the gas by treating the latter with liquid solvents for naphthalene at ordinary or a slightly increased temperature. Even when the temperature of these solvents was raised to almost 30° C. and use also made of solvents, more especially washing oils, which are well known to dissolve naphthalene very readily, it was still impossible to produce a gas free from naphthalene; on the contrary it retained amounts of naphthalene which could not merely be determined by the usual methods of investigation, but were of such a magnitude as to make it likely that the undesired clogging of the passages would take place. Attempts were therefore made to prevent deposits in solid form at least, in the connecting pipes and the gas was carburetted, washing oils for the naphthalene being therefore incorporated therein and the gas treated in this manner left for a time. If the gas for some reason became cool at any point, either in the works or in the main leading to the consumer, to such an extent as to cause the

separation of solid naphthalene, the carburetted oil, which was chosen with a suitably low boiling point, was deposited at the same time, but in liquid form and brought the naphthalene down into solution, the whole being then conveyed to collectors of some kind and removed. If however, there did not happen to be any cooling, the naphthalene vapor and carburetted medium were carried by the gas to the consumer. If one considers the increasing amount of gas, which is produced today at gasworks and has to be conveyed by long-distance mains, it is evident that enormous quantities of the carburetted medium in some cases definitely escape with the gas, and in some cases necessitate a constant supervision and troublesome emptying of the collectors, to which the carburetted medium, containing naphthalene and liquefied if any cooling takes place, is conveyed.

According to the invention the gas is treated with a solvent for naphthalene and permitted to absorb solvent vapors. This however is followed by a cooling of the gas to such an extent that the absorbed solvent vapors are condensed and at the same time remove the naphthalene completely from the gas. Consequently it is impossible by the methods of investigation in practice today, to find any naphthalene in the gas treated by the method forming the subject matter of the invention. The gas purified in this way cannot deposit any naphthalene either on its way through the works, or, if the purification has taken place at any other point, upon being conveyed from this place, even if there should by chance be any unavoidable and undesired cooling of the gas.

The solvent vapors are absorbed at temperatures, which are naturally higher than the cooling temperatures subsequently employed, at which if possible the entire amount of absorbed solvent vapors is to be liquefied again. It has been found especially advantageous to increase the temperatures, at which the gas absorbs the solvent vapors, above 40 and 50° C. to say, 100° C. and thereupon effect the cooling. The minimum temperature of the latter must in its turn be such that the solvent vapors are condensed as com-

pletely as possible, to prevent the solvent which is usually expensive, from escaping with the gas into the pipes. In some circumstances it will therefore be advisable to choose 5 the cooling temperature lower than is absolutely necessary or to subsequently lower the temperature employed for separating the solvent, in order to eliminate any traces of the solvent from the gas and use the solvent for 10 the same or other purposes. If in such a case use is made of temperatures approaching or even below 0° C., the further result obtained is that the gas is completely dried. Gas has already been cooled considerably, even below 15 0° C. for removing the naphthalene from the gas. This has naturally nothing to do with the invention which does not employ either a washing with oil alone, or carburation alone or excessive cooling alone, which, experience 20 has shown, would never attain the object of the invention. Similarly the invention has nothing to do with a method which aims exclusively at obtaining valuable materials, such as for instance gasoline, from a gas and 25 bringing the latter into contact with the same washing oil first at an increased temperature and subsequently at a reduced temperature; by such a method it is probably possible to remove the valuable material concerned from 30 the gas, but not naphthalene, as a treatment of this kind would be equivalent to bringing the gas to be freed from naphthalene into contact exclusively with a washing oil of low temperature. 35 In practice the invention is carried out for instance in such a way that normally treated distillation gas of the usual temperature, with about 15 grms. naphthalene per 100 cbm. is allowed to bubble through a 40 suitable solvent, for instance naphthalene oil, benzene washing oil, steam-volatile constituents of washing oil, tar oil etc. at temperatures of for instance 100° C. The most favorable temperature should however in 45 each case be determined to suit the character of the washing oil. In such a case the liquid washing oil can become sufficiently enriched with naphthalene. In addition however the gas becomes charged with oil particles, which 50 remain in vapor form in the discharging gas. Upon subsequently passing through the cooling stage, these oil particles are deposited with simultaneous absorption of the naphthalene, which is still contained in the gas. 55 The inventors' interpretation is that during cooling, the mist of washing oil vapors first formed, and the subsequent condensing liquid in which the condensed particles of oil separate from the gas, act so to speak with 60 a very great surface development on the traces of naphthalene contained in the gas, and thus eliminate it completely in solution from the gas, which may explain the surprising result of the complete removal of 65 naphthalene from the gas. Accordingly the

solvent should be incorporated with the gas in a minimum quantity such as to ensure the complete washing out of the naphthalene.

The solvent condensate containing naphthalene is naturally separated from the gas, if necessary by reducing the temperature in stages. The solvent recovered in this way is now used for other purposes or, if desired freed more or less from absorbed naphthalene (regenerated) and/or mixed with fresh solvent, and supplied again to the initial stage of the process. If use is made of oils, which can be charged to a high degree with naphthalene, for instance up to 44%, it is possible to manage with comparatively small quantities of oil, which, when the whole process is suitably carried out and the oil condensate returned to the initial washing stage, require during the course of time practically no appreciable addition of fresh oil. 80 85

Any necessary regeneration of the solvent can be effected by cooling or driving off at least a portion of the absorbed naphthalene.

A suitable apparatus for carrying out my improved process is illustrated in vertical section in the accompanying drawing, which shows a vessel *a* having an inlet 1 for receiving the gas after it has been purified by the method heretofore used. This vessel is filled with a suitable washing oil up to or above the level of the inlet 1. The gas is discharged through the inlet 1 into the bottom part of the vessel beneath the surface of the washing oil. This gas is preferably under a pressure of 1½ to 6 atmospheres while the temperature in the vessel is above 30° C. If the gas should be introduced under normal pressure, which is only a few millimeters as measured by a water column, then the temperature of the vessel would preferably be raised to 70° or 80° C. or higher. Coal distillation gas as it is sent over long distance is usually under a pressure of more than 1½ atmospheres, generally 5 to 10 atmospheres, and at such pressure will have a temperature about 100° C. Such gas may be passed through the vessel *a* without previously heating the latter, the oil in the vessel being heated directly by the gas. The gas, which has already been purified by the usual method heretofore used, gives up while passing the oil in the vessel some parts of the remaining naphthalene and benzole which has not been removed by the previous treatment. Vapors of the washing oil are also taken up by the gas as it bubbles through the oil in the vessel. First the vapors of low boiling oil are thus taken up by the gas and flow therewith successively through the cooling vessels *b* and *c*. Here the gas, together with the oil vapors, is cooled and the oil vapors are thereby condensed so that they form a sort of very fine rain of oil which goes down through the gas and takes out therefrom the last remaining traces of naphthalene. Such rain of oil develops a 90 95 100 105 110 115 120 125 130

very large surface which comes in contact with the oil and traces of naphthalene, thereby dissolving or absorbing it and taking it out of the gas. The gas as it leaves the plant 5 at the outlet 2 is completely devoid of any traces of naphthalene.

The oil condensed in the coolers *b* and *c* flows through the pipe 3 into a vessel *d* in which the condensate is allowed to accumulate for a suitable period of time. Here the water which was taken out of the gas by the oil at the same time as the naphthalene is cooled in the lower part of the vessel *d*, while the oil and naphthalene due to their lower 15 specific gravity are cooled in the upper part of the vessel. The water thus separated from the oil is withdrawn through the pipe 4 and the oil is withdrawn through the pipe 5 into the vessel *a* where it again mingles with the 20 heavier oils which have remained therein. Herein a part of the naphthalene contained in the incoming lighter oil is imparted to the heavier oil because the latter has a capacity 25 for dissolving naphthalene at a given temperature more readily than the oils which have a lower boiling point. The lighter oils are therefore partially freed from the naphthalene which they have carried. If they 30 are now evaporated again by passing hot gas through them they are absolutely freed from naphthalene because only the washing oils and not the naphthalene are evaporated.

If a mixture of heavier and lighter oils are treated in this manner, the lighter oils with 35 the lower boiling point apparently flow in a closed circuit, first being evaporated in the vessel *a*, then flowing with the gas through the coolers and returning as condensates to the vessel *a*.

40 After the oil mixture in the vessel *a* has become approximately saturated with naphthalene, the oil may be regenerated or replaced by fresh oil.

Although the invention is not limited to 45 any method of carrying out, and any suitable solvent, that is to say more especially low and high-boiling oils alone or in mixture, may come into consideration, the invention can be carried out with particular advantage and simplicity in cases in which gas is given off at a high pressure, as for instance in long-distance gas pipes. The gas is heated 50 by the high compression and conveyed by a plunger into the solvent which it heats. In such a case the gas at an increased temperature (for instance 100° C.) gives up naphthalene to the oil and becomes charged on the other hand with oil vapors. Seeing however that the gas which has become hot by compression, must be cooled in order to change 55 its volume, before it is discharged into the long-distance pipes, the corresponding coolers can at the same time be used for condensing the washing oil vapors, while completely removing the naphthalene from the

gas, which is now discharged into the pipes.

Similarly however the organic solvent or its vapors, with which the gas is allowed to be charged, either in the gas phase or during condensation in the cooling stage, can absorb in addition to traces of naphthalene also traces of benzene and other impurities, which therefore, dissolved in the solvent, can be condensed and removed with the latter.

The substances which have been found particularly suitable for such a method are solvent naphtha II, the low-boiling steam-volatile parts of naphthalene oil or benzene washing oil, more especially the coal tar oils boiling between 160-220° C., which consequently have a considerably greater capacity of absorbing naphthalene at an increased temperature than at room temperature and therefore when charged and saturated with naphthalene etc. at an increased temperature, 85 deposit naphthalene during the subsequent cooling. If such oils are employed, the gas must be carefully cooled, to prevent any solvent escaping with the purified gases and being wasted. If the gas is kept under pressure during purification, the relative loss in solvent, calculated on the volume of the gas under atmospheric pressure, will be extremely small. Care will have to be taken however 90 that the gas leaves the cooling stage at temperatures of 20° C. or less. A complete precipitation of the solvent could be obtained by excessive cooling of the gas to 0°, whereby 95 an absolutely drying of the gas would also be obtained. Cooling to this extent requires 100 however large and correspondingly expensive coolers.

Losses in washing oil and such low final temperatures of 20° C. and less, can be avoided however by using higher-boiling oils than ordinary benzene washing oil, anthracene oil, solvent naphtha II etc., i. e. higher or high-boiling oils, such as for instance quickly distilled benzene washing oil, quickly distilled 105 anthracene oil etc. These high-boiling oils do not increase their absorption capacity for naphthalene, benzene, etc. in the case of increases in temperature, to the same extent as the low-boiling oils, i. e. those boiling up 110 to about 220° C. Consequently if a high-boiling oil is saturated at room temperature with naphthalene, its capacity of absorbing naphthalene is not increased by a rise in temperature alone, to such an extent that it would completely dissolve and remove 115 naphthalene from the gas to be purified, at an increased temperature. In other words: Purification of the gas with high-boiling oils is not without further preliminary as simple and complete as with low-boiling oils. If 120 however naphthalene, benzene, etc. are expelled artificially from the high-boiling washing oil, as soon as this washing oil is sufficiently enriched with the naphthalene etc., and the oil regenerated in this 125 way

thereupon re-introduced into the washing stage, it is possible completely to eliminate traces of naphthalene, benzene, etc. from the gas, without having to reduce the temperature of the gas to be purified, in the cooling stage to about 20° C. or lower. On the contrary in that case a completely purified gas is obtained if it leaves the cooler at about 30-40° C. Losses in this washing oil 10 in the discharging gas need not be feared nevertheless, even when working with only a slight or without pressure in the gas, because the tension of such high-boiling washing oils is extremely small at room or moderately high temperature, i. e. about 30-40° C.

If therefore use is made solely of higher or high-boiling washing oils for carrying out the invention, the gas to be purified will again 20 be allowed to bubble up through the washing oil at an increased temperature, in any case above 30° C. and preferably above 100° C. It will also be advantageous to allow the gas to become charged with vapors of this washing oil and thereupon condense these washing oil vapors in the cooling stage. The condensate will however in this case not be cooled simply to room temperature and again introduced into the washing stage, but the absorbed naphthalene will be expelled therefrom, at least in part, by distillation; only then is this washing oil introduced as fresh oil into the washing stage.

A further method of carrying out the invention is finally to employ an oil mixture for washing the gas, which mixture consists of high- and low-boiling oils, i. e. preferably mainly of oils, which boil above 220° C. and the remainder of oils, which boil below about 40 220° C.

If the gas to be purified is allowed to bubble up (immersed washing) at an increased temperature above 30° C., preferably above 100° C., through an oil mixture of this kind, 45 naphthalene, benzene, etc. are removed by the oil mixture from the gas. In addition the gas becomes charged with vapors consisting chiefly of the low-boiling oils, which are now condensed in the cooling stage, form 50 a fine precipitate and at the same time dissolve any traces of naphthalene, benzene, etc. in the gas and remove them. The condensates, after separation from water, can be returned into the immersing stage, mix 55 with the oils there, give up a portion of their naphthalene content to the high-boiling oils more especially and are thus made capable of passing again as solvent vapors into the gas to be purified, and of becoming enriched 60 afresh with naphthalene, benzene residues etc. The low-boiling constituents of the oil mixture thus perform so to speak a circuit between the immersing and cooling stage, while the higher-boiling constituents of the 65 oil form a kind of naphthalene accumulator

in the immersing stage, which is gradually increasingly enriched with naphthalene. The absorption capacity of the oil mixture for naphthalene is in such a case considerably higher than that of high-boiling oils alone, 7 while on the other hand the vapor pressure of the mixture and at the same time the possible losses in oil are less than when low-boiling oils are used alone. A regeneration of the oil mixture is not necessary for some time. Consequently the naphthalene must not be crystallized out after each condensation, before the washing oil is returned to the immersing stage, as is the case when high-boiling oils are used.

When however the oil mixture is enriched with naphthalene to such an extent that a complete purification of the gas is no longer obtainable, it is fed to the separator. In such a case the low-boiling oil is first distilled off, and the crystallized naphthalene expelled by centrifugal force from the residue in the still after cooling to room temperature. By quick distillation it is then possible to obtain the high-boiling constituents of the washing oil free from naphthalene again. These can be added again to the residue from the light oil in any desired proportion, whereby a mixture of washing oil ready for use is again obtained.

When the water cooler is adjusted to such an extent that the purified gas flows off at temperatures of about 25-45° C., a further intense cooling of the gas with freezing liquor of about 5° C. has proved advantageous. As the gas in such a case is already completely free from naphthalene, this intense cooling has nothing to do with its purification from naphthalene. On the contrary this intense cooling is merely intended to effect a thorough drying of the gas and the condensation of any vapors of washing oil that may have been carried along. When the gas then leaves the super-cooler at a temperature of about 12° C. it is discharged completely free from 11 condensate and dry into the pipe mains.

This stage of the process for drying the gas can moreover be used when washing with low- (up to about 220° C.) or high- (preferably above 250° C.) boiling washing oils alone or when a suitable mixture of the two kinds of washing oil is used.

It is clear that the method forming the subject matter of the invention, however it may be carried out, is particularly economical for the purification of long-distance gas, because the latter owing to the necessary compression is heated to a high temperature and the washing with oil thus takes place at 12 this temperature, while on the other hand a cooling must also take place, and the last traces of naphthalene, etc., be washed out by the rain of washing oil condensate.

Moreover the invention is in no way lim- 13

ited to the absorption of naphthalene by the washing oil taking place in the immersion stage only, or super-purification taking place exclusively in the cooling stage by the condensed washing oil vapors. It is of no importance for the invention what processes occur in the immersion stage and in the cooling stage, whether for instance in the immersion stage the majority of the naphthalene is removed from the gas and a subsequent purification of the gas takes place in the cooling stage by means of the solvent carried along from the immersion stage, or whether no naphthalene is given off by the gas in the immersion stage, but the gas is only charged with solvent vapors and the whole purification takes place in the cooling stage, or whether finally at certain periods of the purification process when the oil is very highly charged with naphthalene, a portion of the naphthalene is carried from the oil in the immersion stage into the cooling stage, and returns, together with the condensate precipitated in the cooling stage, in a cycle into the immersion stage. On the contrary the chief point is that it is always possible completely to eliminate the naphthalene from a gas charged with naphthalene and that consequently the gas finally leaves the washing apparatus in a perfectly pure state.

In order to avoid losses in washing oil, it is possible instead of employing or in addition to employing intense cooling, to treat the gas with a high-boiling oil absolutely free from naphthalene, which is prepared in a very simple manner by allowing the oil to be traversed at an increased temperature by air or gases free from oxygen, such as for instance flue gases, coke furnace gases. By this means all naphthalene is removed from the oil, without appreciable amounts of oil passing over into the gas. A high-boiling oil free from naphthalene and prepared in this way absorbs the constituents of the washing oil, boiling between 160-200° C. from the finely purified gas, if the latter is for instance sprayed with this oil, and the gas is therefore discharged into the pipes without carrying washing oil with it.

50 What I claim is:

1. The method of removing traces of naphthalene from coal distillation gas previously purified in the usual way, which comprises treating the gas in a first stage at a temperature above 40° C. with solvents for naphthalene, said solvents forming a mixture of light and heavy oils, thereby causing the incorporation of the vapors of said solvents in the gas, thereupon cooling the gas in a second stage, thereby causing simultaneously the condensation of said vapors of the solvent and the traces of naphthalene, this second stage being performed before delivering the gas to the main, then delivering the condensed solvents back to the first stage for remixing with oils

and thereby increasing the temperature, thereby repeating the process.

2. The method of removing traces of naphthalene from coal distillation gas previously purified in the usual way, which comprises 70 treating the gas in a first stage at a temperature above 40° C. with solvents for naphthalene said solvents forming a mixture of light and heavy oils, thereby causing the incorporation of vapors of said solvents in the gas, then cooling the gas in a second stage and thereby causing simultaneously the condensation of said vapors of the solvent and the traces of naphthalene, then further cooling 75 the gas in a third stage to complete condensation of the solvents the second and third stages being performed before delivering the gas to the main, and then delivering the condensed solvents back to the first stage for re-mixing with the oils and thereby increasing 80 the temperature, thereby repeating the process.

3. The method of removing traces of naphthalene from coal distillation gas previously 85 purified in the usual way, comprising the compression of the gas to a pressure adapted for long distance transmission, passing the gas so compressed and with raised temperature in a first stage through solvents for naphthalene, thereby causing the incorporation of 90 vapors of said solvents in the gas, then in a second stage cooling the gas and thereby causing the condensation of the vapors of the solvents which also take up from the gas the 95 traces of naphthalene, and then separating 100 this condensate from the gas before delivering the gas to the main.

In testimony whereof I have signed my name to this specification.
